SELF-HEATING CONTAINER

Eugene J. Rivoche and Lev Sukacev,
Washington, D. C.

Application November 3, 1950, Serial No. 193,868

36 Claims. (Cl. 126—263)

1

This invention relates to self-heating containers for the packaging of foods or other materials which it may be desired to heat without recourse to extraneous heating agents. Such containers are particularly adapted for emergency use by the Armed Forces and others under conditions where it is impossible or impractical to prepare hot foods under the usual conditions.

The self-heating containers of the present invention embody improvements on the type of self-heating container disclosed in the application filed by Lev Sukacev on June 28, 1950, Serial No. 170,757. In that application there is disclosed and claimed a self-heating container in which the container for the foods which it is desired to heat is mounted for telescopic movement in an outer supplemental container, and lime or other material, which on reaction with water liberates heat and in doing so expands in volume, is interposed between the bottom of the food container and the outer supplemental container. The telescopic mounting of the food container within the outer container permits expansion of the lime when water is added without subjecting either container to excessive pressure, and thereby makes it possible to construct both containers of relatively light-weight material.

An important consideration in any self-heating container is the efficiency of the transfer of heat from the exothermic material to the food container, particularly if the container may be used in cold climates where the heat necessary to bring the food to the desired temperature is greater, and where dissipation of liberated heat may be greater than otherwise.

As the amount of exothermic material needed to bring the food of the container to the desired temperature is inversely proportional to the efficiency of heat transfer thereto from the exothermic material, a high heat transfer efficiency permits the use of less of the exothermic material, as well as making it possible to use a smaller container, an important factor where transportation space is of importance.

When water is added to burnt lime, the resulting exothermic reaction, or slaking, causes the body of lime to swell or expand, if unrestrained, to approximately three times its original size. The expanding or swelling of the lime reduces the heat conductivity thereof by as much as 90 to 95%.

When the exothermic material is lime or other material which expands appreciably when

water is added to it, some expansion is desirable in order that it shall not be necessary to use materials for the container which will be strong enough to resist the entire pressure developed by the expanding exothermic material, but unlimited expansion is not desirable since it too greatly reduces conduction of heat to the food container. Consequently, one of the features of the present invention is to provide a self-heating container of the type disclosed in the aforesaid application in which the food container has only a limited outward movement relative to the outer container, with the outward movement being stopped when the slaking lime has expanded to from about one and one-half to two and one-half times its original volume, and before it has reached its normal unrestrained expansion. Advantageously, the outward movement of the food container may be stopped when the lime has expanded to about twice its original volume. By thus permitting a partial expansion only of the lime, the lime will be maintained in a somewhat compressed, more dense state, and its heat conductivity will be much greater than that of the lime in its fully-expanded state. Also, as the bottom of the food container is the restraining force on the expanding lime, the lime will cause a good heat-conductive contact to be made with the food container, which also enhances the conduction of heat from the lime to that container. The fact that neither the food container nor the outer supplemental container has to resist the full expansive force of the lime permits the use of relatively light material for construction of both of those containers, and thereby lessens the cost of the self-heating container. The present invention further provides for increased conduction of heat from the exothermic material to the food container by providing metal or other elements of good heat-conducting properties which, throughout all stages of expansion of the lime, are maintained in contact with the body of lime and the food container and act as conductive paths for transferring heat from the hot lime to the food container.

The dissipation of heat from the exothermic material, other than to the food container to be heated, is prevented, or largely retarded, by suitable insulating means, and by enclosing the entire self-heating container in an enclosing casing of cardboard or other material having relatively good insulating properties which insulates it from the surrounding atmosphere and also prevents air currents from picking up

heat both from the food container and the outer supplemental container.

Whereas the self-heating container of theforesaid application included a receptacle for water to be added to the exothermic material, the container of the present invention is packaged dry, that is, without water to be added to the exothermic material, and special means are provided to facilitate the addition of water and also to assure that the proper amount of water to liberate the maximum heat from the exothermic material is added.

Other features of the invention will be clear from the following more detailed description taken in connection with the accompanying drawings. However, it is to be understood that such further description is by way of exemplification and the invention is not limited thereby, except to the extent set forth in the appended claims.

In the drawings:

Fig. 1 is a vertical cross-sectional view of a self-heating container embodying the invention and enclosed in an insulating casing.

Fig. 2 is a view similar to Fig. 1 showing the relative position of the parts after the exothermic material has expanded on reaction with water,

Fig. 3 is a vertical sectional view of the lower portion of the self-heating container removed from its insulating casing and showing the manner in which water is retained on the bottom of the outer supplemental container for passage to the exothermic material.

Fig. 4 is a horizontal cross-sectional view, partly broken away, on line 3—3 of Fig. 1.

Fig. 5 is a perspective view, with parts broken away, of one of the expandible containers for the exothermic material.

Fig. 6 is a vertical cross-sectional view of a modified form of a self-heating container embodying the invention, with the insulating casing removed,

Fig. 7 is a horizontal cross-sectional view on line 7—7 of Fig. 6,

Fig. 8 is a vertical cross-sectional view of a self-heating container having a space within the outer confines of the food container for the exothermic material, also shown with the outer insulating casing removed, and

Fig. 9 is a vertical cross-sectional view of a self-heating container embodying the invention and particularly adapted for the thawing and heating of frozen foods, removed from its outer insulating container.

Referring now to the drawings, and first to the form of the invention shown in Figs. 1 to 5, the material which is packed for subsequent heating, hereinafter referred to as "food" but which may be material of any kind, is hermetically sealed in a container 1 of metal or other material having good heat conductivity, in a manner well-known in the food packaging art. Such containers may be the usual tinned or lacquered metal cans.

The food container 1 is mounted for subsequent telescopic movement in an outer, open-ended supplemental container 2 of the same shape as the container 1 and having a bottom 3 and side walls 4. The food container 1 and the supplemental container 2 may be of any desired shape and proportions, although normally, a round, relatively flat food container is preferred. When the food container has relatively little height, the heating of the food

therein, in the manner set forth below, as facilitated.

The side walls 4 of the outer container have an inside diameter sufficiently larger than the outside diameter of the food container to just compensate for the increased diameter caused by the crimped seal 5 at the periphery of the bottom of the food container. Thus, while the food container may move freely within the outer container, the crimped seal 5 lies sufficiently close to the outer container to effectively prevent any appreciable amount of the exothermic material being forced past it.

After the food container has been placed in the outer container 2, the outer free edge of the side walls 4 are bent or curled inwardly to provide an internally-extending flange or projection 6 to form a stop, which on outward movement of the food container is engaged by the crimped seal 5 and thereby limits the outward movement of the food container.

If the food is not packaged in a container having an outwardly-extending crimped seal which can engage the inwardly-extending flange or projection 6, a suitable outwardly-extending flange or projection should be formed on the lower portion of the food container. Such a projection may be in the form of an annular ridge formed by grooving from the inside, as in a modification to be described later, or spaced projections formed by indenting from the inside.

For the purpose of heating the food within the container 1, exothermic material 7, that is, a material which will react with water to liberate heat, is placed between the bottom of the food container 1 and the bottom of the outer supplemental container. The exothermic material may be of any known material or composition which will react with water to liberate a substantial amount of heat, but we prefer burnt lime as it is readily available, is cheap, and on reacting with water liberates large amounts of heat.

The exothermic material 7 is placed in sector-shaped receptacles 8 of aluminum or other metal having good heat-conductive properties. Four such containers are used but a lesser or greater number may be used if desired. If the food container is quite large, six or even eight or more such containers may be used. Each of the sector-shaped receptacles comprises a lower tray portion 9 and a cover portion 10 having downwardly-extending side flanges 11 and 12 which make a sufficiently good contact with the upwardly-extending sides 13 of the lower tray portion to readily conduct heat from the tray portion to the top of the cover portion. However, the frictional engagement of the flanges of the cover portion with the side walls of the tray portion is not such as will prevent relative movement of the cover and tray portions on expansion of the exothermic material when reacted with water.

The cover portion of each of the receptacles for the exothermic material is contoured to accurately conform to the contour of that portion of the bottom of the food receptacle with which it is in contact, so that the bottom of the food container will lie in close, heat-conductive contact with the top of the several receptacles for the exothermic material. When the bottom of the food receptacle is reinforced with annular, outwardly-extending grooves or ribs, the several receptacles 8 will have aligned arcuate grooves

complementary to such grooves or ribs of the food container.

The top of the cover portions 10 preferably are solid to provide a continuous heat-conducting surface to the bottom of the food container, although, if desired, one or more openings may be placed in the top of the cover portion to permit direct contact by the lime in the receptacles with the bottom of the food container.

To permit access of the water to the exothermic material, as described later, the bottom of the tray portions are perforated as at 14. The perforations advantageously are so arranged that continuous straight metallic paths for the conduction of heat are provided both to the straight radial walls and to the arcuate outer wall of the tray portions. The perforations advantageously are formed by a punching operation which will leave inwardly-extending flanges or burrs 15 at the sides of the perforations. Such flanges or burrs when the exothermic material is reacted with water, will assist in transferring heat from the body of the exothermic material to the metal walls of the lower tray portions.

The straight radial side walls and the outer arcuate walls of the cover portions 10 are of a depth sufficient to extend below the bottom of the lower tray portion 9, the depth of the outer arcuate wall is greater than the straight radial side walls, and to accommodate such additional depth the periphery of the bottom of the outer supplemental container 2 is grooved outwardly as at 16 to provide a trough into which the arcuate outer wall of the cover is received.

The depth of the flanges 11 and 12 is such that when the exothermic material has expanded and moved the cover members 10 relative to the tray portions 9 the maximum amount permitted by the limiting flange 6, they still will contact the side walls of the tray portions 9 and provide a good conductive path for the conduction of heat from the exothermic material to the top of the covers and to the bottom of the food container.

In the drawings the flanges of the covers are shown as making a close fitting contact with the outside of the side walls of the tray portions. If desired, the flanges of the covers can be received within and make a close fitting contact with the inside of the side walls of the tray portions.

To further assist in the transfer of heat from the internal portions of the body of reacting exothermic material to the top of the receptacles 8 and from them to the bottom of the food container, a mass of metal shavings or other flexible springy material 17 of high heat conductivity, such as shavings of aluminum, copper, etc., are embedded in the exothermic material in each of the receptacles 8. These shavings normally are in the form of a springy mass several times the depth of the receptacle 8 so that when the covers 10 are placed on the tray portions and pushed to the position shown in Fig. 1, the mass of shavings will be compressed. As the receptacles expand under the expansive force of the reacting exothermic material, the springy mass of shavings 17 will open up and maintain contact with the covers 10 and form a metallic path for good conduction of heat from the mass of expanded exothermic material to the covers 10 of the receptacles, from which the heat is conducted to the bottom of the food container.

Instead of using a springy mass of metal shavings or the like to conduct heat from the mass of exothermic material to the covers of the receptacles, springs, or flexible members secured to the

covers 10 and extending down into the mass of exothermic material, as disclosed in other embodiments of the invention to be described, may be used.

5 A layer 18 of exothermic material of the order of one-tenth inch in thickness is interposed between the bottom of the sector-shaped receptacles 8 and the bottom of the outer container 2 and serves to insulate the receptacles 8 from the container 2 and thereby prevents or greatly retards the passage of heat from the receptacles 8 to the outer container. The layer 18 also serves to maintain the lower edges of the flanges 11 and 12 of the cover portion spaced from the bottom of the outer container so that they will not provide a path for the conduction of heat from the receptacles 8 to the outer container. To further insulate the receptacles 8 from the outer container and thereby further reduce loss of heat, rings 19 of suitable insulating material are interposed between the arcuate flanges 12 of the several receptacles 8 and the side wall of the outer container.

25 The exothermic material normally is maintained hermetically sealed between the food receptacle and the outer container 2 by a sealing band 20 extending around the side walls of the food container and overlying the upper end of the side walls of the outer container 2. The sealing band may be an adhesive tape, a strip of plastic, or rubberized, or other appropriate material. The sealing band 20, while adequate to hermetically seal the container, is sufficiently weak to rupture under the expanding force of 35 the exothermic material should its removal be overlooked before the container is put into use. If desired, a metal tape, wire, or band 21 may be wound about the food container and the outer container from top to bottom to give protection 40 against removal of the food container from the outer container until heating of the material in the food container is desired.

Water is admitted to the exothermic material in the receptacles 8 by punching holes in the bottom of the outer container 2 through which it passes. To facilitate the punching of such holes, the bottoms of the receptacles 8 are formed with a series of slight indentations 22. As the self-heating containers are designed primarily for 45 emergency use, or for use where punching tools may not readily be accessible, a nail or other punching tool may be packed in the container for use in making the punch holes for the entry of water.

55 A gauge ring 23 is mounted about the lower portion of the outer container 2 and has its inner end 24 turned inwardly to form an inwardly-extending flange which makes a frictional sliding fit with the side walls of the outer container. Outward movement of the gauge ring is limited 60 by engagement of the inwardly-extending flange 24 with an outwardly-extending projection 25 adjacent the bottom of the outer container. The width of the gauge ring 23 is such that when the ring is moved outward to its maximum extent, and the container inverted, the ring will define a 65 space having a volume equal to the volume of water which should be added to the exothermic material to give the maximum heating effect.

70 To further prevent dissipation of heat when the container is being used, it is completely enclosed in an outer casing 26 of cardboard, insulating board, or the like. The casing 26 comprises a lower receptacle 27 and a cover 28 having a depending side wall 29 of sufficient depth to main-

tain contact with the side wall of the lower receptacle when the food container has been raised to the maximum amount permitted by the limiting flange 6 under the expansive force exerted by the exothermic material. A sealing strip 20x, similar to the band 20, may normally secure the cover 28 in place on the receptacle 27.

When the container is to be used, it is removed from the casing 26 and the retaining band 21 and the sealing strip 20x are removed. The container then is temporarily inverted, holes punched in the bottom of the outer receptacle for the passage of water to the exothermic material, and the gauge ring 23 lifted to the position shown in Fig. 3. The space enclosed by the gauge ring 23 is then filled with water and the container left inverted until all of the water has passed through the punch holes in the bottom of the outer container and into the exothermic material. The container then is turned back to its normal position with the exothermic material at the bottom so that the heat will rise upwardly therefrom in a normal manner and be conducted by the metallic conductive path heretofore described to the food container. The food container is then opened before it becomes too hot, and to permit occasional stirring of the food during the heating operation to facilitate transfer of heat to all portions thereof, and is replaced in the outer casing 26 and retained therein until the food in the food container is thoroughly heated.

The exothermic material on reaction with water puffs or expands. In the case of burnt lime, the expansion if unrestrained would result in the lime being increased to approximately three times its original volume, with a reduction of its normally low heat conductivity by about 90 to 95%. After the lime has expanded to approximately two times its original volume, the food container will have been lifted to an extent such that the bottom crimped seal 5 engages the inwardly-extending flange 6 of the outer container and further outward movement of the food container is prevented. However, the generation of gas continues and creates an internal pressure within the receptacles 8 which forces their covers 10 tightly against the bottom of the food container so that a good heat-conductive contact is made.

The engagement of the crimped seal 5 with the flange 6 also takes place before the side flanges 11 and 12 are separated from contact with the upwardly-extending side walls of the tray portions 9. Thus, the contacting side walls of the tray and cover portions of the receptacles also provide a good heat-conductive path to the top of the covers in contact with the bottom of the food container.

As the heat conductivity of the lime progressively decreases on expansion of the lime, the controlling of the extent of the expansion of the lime to less than its normally free expansion also makes the lime itself a better conductor for transferring heat to the covers and from them to the food containers.

As the lime expands and separates the cover and tray portions of the receptacles 8, the mass of metal shavings 17 which have been maintained under compression during the shipping and storage of the container expands and continues to maintain contact with the undersurface of the cover portions 10 and form paths for good conduction of heat from the interior parts of the lime in each receptacle. The expansion of the lime also tends to some extent to expand the mass of metal shavings and to cause them to

maintain a good heat-conductive contact with the cover portions of the receptacles 8.

The form of self-heating container shown in Figs. 6 and 7 generally is the same as that disclosed in Figs. 1 to 5, and comprises a food container 30, and an outer supplemental container 31 having a bottom 32 and side walls 33, the outer ends of which are curled inwardly to provide a flange 34 which, on expansion of the exothermic material, is engaged by an outwardly-extending bulge 35 at the periphery of the lower portion of the food container to limit further outward movement of that container under the expansive force of the exothermic material.

15 The sector-shaped receptacles 36 for the lime or other exothermic material are generally similar to those of the preceding figures and comprise tray portions 37 having side flanges 38, perforated bottoms 39, and cover portions 40 having solid tops 41 and depending side flanges 42 which have a close fit with and extend below the side walls of the tray portion. As in the preceding figures, the arcuate outer side flanges of the covers, which are of greater depth than the radial side walls of the tray portions, are received in an annular groove or trough 43 at the periphery of the bottom of the outer container. However, in this embodiment of the invention the radial side walls of the trays and the cover portions do not extend quite to the center of the container and do not meet one another. With this arrangement, a central space 44 is provided at the apex of each of the sector-shaped receptacles into which water may enter and from which it may pass to the several receptacles through the openings at their several apices.

40 This form of the invention is adapted for use with food containers which have a concave bottom, and the several receptacles 36 are curved so that at least their cover portions accurately conform to the curvature of the bottom of the food container so as to make good heat-conductive contact therewith. The receptacles 36 also are insulated from the outer container by an insulated layer of lime or other exothermic material 45, and a ring 45' of insulating material is interposed between the outer flange of the cover portions 40 and the outer container to prevent transfer of heat when the container is put into operation.

45 The depth of the groove or trough 43 is sufficient that, with the concave bottom 32 of the outer container, it provides a space adequate, when the container is inverted, to contain sufficient water to properly activate the exothermic material in the receptacles 36.

50 The concave bottom 32 of the outer container is provided with slight indentations to facilitate punching.

55 Instead of a sealing band overlapping the top edge of the outer container 31 and being secured to the side walls of the food container, like the band 20 previously described, the exothermic material in the receptacles 36 is hermetically sealed by a metallic cover 46 for the outer container 31 having a side flange 47 sufficiently wide that when the cover is placed over the outer container with the food container in it, it will overlap the side walls of the outer container. Hermetic sealing is obtained by soldering the lower edge of the flange 47 to the side wall of the outer container with a solder which is sufficiently weak to rupture under the expansive force of the exothermic material should the cover 46 not be removed before the container is put into operation.

Instead of embedding metal shavings in the body of the exothermic material placed in the receptacles to transfer heat from the body of the expanded exothermic material to the covers of the receptacles 36, each receptacle contains a spring member 48 having a flat top section 49 lying in close heat-conductive contact with the top of the receptacle, and a plurality of radially-extending legs 50 and 50'.

In order that the legs will extend to different parts of the body of the exothermic material for the purpose of conducting heat therefrom to the flat top section, the legs 50 extend radially outwardly, while the legs 50' extend radially inwardly from the periphery of the central flat top section 49. When the receptacles are closed with the springs in them, the tops of the receptacles exert a pressure on the legs which spreads the legs 50 outwardly and the legs 50' inwardly, as shown in Figs. 6 and 7. When the exothermic material expands and lifts the cover portions 40 of the receptacles 36 and the food container, the legs 50 and 50', which were under compression, raise the covers 40 and maintain them in tight heat-conductive contact with the bottom of the food container. The legs 50 and 50' of the spring member conduct heat from the mass of the exothermic material to the central flat top section 49 from which it is conducted to the top of the receptacles 36 and by them to the bottom of the food container.

The self-heating containers of this form of the invention will be enclosed in an insulating casing, the same as the container of the preceding figures; and otherwise are the same and put into operation in the same manner as the container of that embodiment of the invention.

Fig. 8 illustrates a somewhat simplified design of the self-heating container. In this embodiment of the invention, the metallic food receptacle 52 has its bottom formed with a dome-like portion 53 which extends into the food container a distance equal approximately to one-half its height. The food container is completely enclosed and hermetically sealed within an outer supplementary container 54. The top of the outer container is removably connected to the body portion thereof by a sealing strip 56 which may be wound onto a suitable key when the cover is to be removed. Such means for hermetically sealing metal containers are well known in the packaging art and are used extensively in the hermetic sealing of packaged coffee.

The side walls of the outer container are provided with an inwardly-extending peripheral groove or circumferentially spaced indentations 57 for engagement by the crimped sealing flange 58 at the periphery of the bottom of the food container to limit outward movement of the food container.

The space within the dome-like portion 53 and the space between the bottom of the food container 52 and the bottom of the outer container 54 is filled with burnt lime or other exothermic material which will react with water with resultant expansion and liberation of heat.

As in the previously-described embodiments of the invention, the bottom of the outer receptacle is provided with slight indentations 59 to facilitate the punching of holes for the passage of water to the exothermic material when the container is to be put into operation.

The side walls of the outer container 54 extend below the bottom wall of that container to provide a circumferential flange 60 of adequate depth

to define a space just sufficient to receive an amount of water to properly activate the exothermic material.

To facilitate the transfer of heat from the interior parts of the exothermic material, metal shavings such as are shown in Figs. 1 to 3, or metal springs, such as are shown in Fig. 6, may be embedded in the body of exothermic material; or chains or other flexible members 61 of good heat-conductive material may be soldered to the bottom of the food container and extend into the body of exothermic material. As the food container 52 is raised under the expansive force of the exothermic material, such flexible members provide a good heat-conductive path from the interior of the body of exothermic material to the bottom of the food container.

The provision of the dome-like portion 53 brings the source of heat into the central portion of the food in the food container and thereby enables the food to be heated more quickly, since the heat does not have to travel as great a distance to the food in the more remote portions of the food container; and also because a greater heating surface is provided for the transfer of heat from the exothermic material to the food within the food container.

In Fig. 9 we have shown a self-heating container which is particularly adapted to the thawing and subsequent heating of frozen foods.

In this embodiment of the invention, the construction of the food container, its outer supplementary container and the receptacles for the exothermic material are the same as the corresponding parts of Figs. 1 to 3 except that the gauge ring 23 is omitted at the bottom of the container and the bottom of the outer supplemental container 3^a is dished to provide a space to receive water to activate the exothermic material, and outward movement of the food container is limited by an inwardly-extending circumferential groove 6^a in the side wall of the outer container rather than by an inwardly-extending flange portion at the top of the side wall of that container. In this embodiment of the invention, the same reference characters primed are used to designate those parts which correspond to similar parts of the self-heating container shown in Figs. 1 to 3.

Frozen foods are very poor conductors of heat. Therefore, when frozen foods are to be heated, the efficiency of the heating can be greatly increased if the heating is done in two stages and with separate bodies of the exothermic material; one stage and one body of exothermic material being used to thaw the frozen food, and the second stage and the second body of exothermic material being used to heat the thawed food to the desired temperature. To that end, the self-heating container in this embodiment of the invention includes a supplemental body of the exothermic material 63 contained in a tray or receptacle 64 of aluminum or other good heat-conductive material on top of the food container. The bottom of the receptacle 64 is shaped to accurately conform to the top of the food container 1' so that it will have a good heat-conductive contact therewith.

A springy body of aluminum or other metal shavings 17^a, or of any of the other forms of heat-conductive means heretofore described, is embedded in the exothermic material 63 to facilitate the transfer of heat from the inner parts of the exothermic material to the bottom of the receptacle 64 when that body of exothermic material is being used to thaw the frozen food.

A cover 65 fits over the receptacle 64 and has a depending side wall which extends to adjacent the bottom of the outer container 2' and is hermetically sealed thereto by a sealing strip 66 to prevent access of moisture of the air to the exothermic material in the receptacles 8' and 64. The top of the cover member 65 has slight indentations 67 to facilitate punching to form holes for the admission of water to the exothermic material 63 when the heating effect thereof is to be utilized to thaw the frozen food.

The peripheral edge of the top of the cover member 65 is provided with an outwardly-extending flange 68 which limits outward movement of a gauge ring 69, which, like the gauge ring 23 of Figs. 1 to 3, is provided to define a space to receive a supply of water just sufficient to activate the exothermic material 63. Outward movement of the gauge ring 69 is limited by an inwardly-extending flange 70 at its inner end engaging the outwardly-extending flange 68 of the cover 65.

The entire unit above described is enclosed in a casing 26^a of cardboard or other insulating material. The cover of the casing 26^a normally is secured in place by a sealing strip 30^a.

When the self-heating container of this embodiment of the invention is to be put into operation, the sealing strip 30^a is removed and the self-heating unit removed from the insulating casing 26^a. The sealing strip 66 is then removed. Holes are then punched through the indentations 67, the gauge ring 69 lifted until the flange 70 at the lower edge thereof engages the flange 68, and the space defined by the gauge ring filled with water. As soon as the water has passed through the punched holes into the lime or other exothermic material, the unit is inverted and put back into the casing with the receptacle 64 for the exothermic material 63 at the bottom and permitted to remain therein until all of the heat given off by the exothermic material is absorbed by the frozen food.

As the lime or other exothermic material expands on reaction with the water, the wall of the receptacle 64 in contact with the food container will be pushed tightly against the food container in good heat-conductive relation thereto. Also, the expansion of the lime will cause both the food container and the outer supplemental container 2' to be raised with the cover member 65.

After the frozen food has absorbed the heat from the exothermic material, the unit is again removed from the casing and the cover member 65 and the receptacle 64 both removed and discarded. The exothermic material in the receptacles 8' is then activated and the food, now completely thawed, is heated in the manner previously described in connection with the embodiment of the invention shown in Figs. 1 to 5.

Ordinarily, means will not be provided to limit the expansion of the exothermic material 63, since the use of such means might interfere with the ready removal of the receptacle 64 after the heat of the exothermic material 63 has been utilized to thaw the frozen food.

In order to facilitate the inward turning of the upper edge portions of the side walls of the outer supplemental containers to form the limiting flanges shown in Figs. 1, 2 and 6, after the food container has been inserted into the outer container, a wire ring 71 is dropped into the space between the side walls of the food container and the outer container to rest upon and be supported by the outwardly extending crimped seal at the lower peripheral edge of the food container to

70

75

act as an anvil about which the upper edge of the outer containers may be turned during the flanging operation.

While all embodiments of the invention above described are dry packs, in that none of the units is provided with water to activate the exothermic material, it is to be understood that, if desired, the several forms of the self-heating containers specifically described may be modified to include a water receptacle such as is disclosed in the fore-said application.

In the several forms of the invention described, the heat generated by the reaction of the exothermic material with water is utilized to the maximum extent in heating the food, and dissipation of heat to the surrounding atmosphere is maintained at a minimum. Consequently, less of the exothermic material is needed to bring the food to a predetermined temperature, and the overall size of the self-heating containers may be smaller than otherwise. Also, the invention provides a self-heating container in which all of the exothermic material is between the bottom of the food container and the bottom of the outer container, and good heat-conductive paths are provided for conducting the heat therefrom to the food in the food container.

Various changes may be made in the details of the construction of the various self-heating containers without departing from the invention or sacrificing the advantages thereof.

We claim:

1. A self-heating container comprising an outer container, a food container of heat-conductive material within the outer container and telescopically movable therein, an exothermic material which on reaction with water liberates heat and expands between adjacent ends of the food container and the outer container, and means for limiting telescopic movement of the food container within the outer container when the food container is subjected to the force of the expanding exothermic material.

2. A self-heating container as defined in claim 1 in which the limiting means includes cooperating engaging portions carried by the outer container and the food container, respectively.

3. A self-heating container as defined in claim 2 in which the amount of exothermic material between the food container and the outer container is such that the cooperating portions carried by those containers will engage and limit telescopic movement of the food container while the exothermic material still is tending to expand when reacting with water.

4. A self-heating container as defined in claim 3 in which the outer container is enclosed in a telescoping insulating casing.

5. A self-heating container as defined in claim 3 in which the outer container has one end open and the cooperating means carried thereby for limiting telescopic movement of the food container is positioned adjacent the open end thereof.

6. A self-heating container as defined in claim 5 in which the cooperating limiting means carried by the food container is an outwardly-extending projection adjacent the inner end of the food container.

7. A self-heating container as defined in claim 5 in which the outwardly-extending projection of the food container is continuous and its outer edge lies closely adjacent the inner surfaces of the side walls of the outer container to prevent substantial passage of exothermic material, when the

13

exothermic material is activated by reaction with water.

8. A self-heating container as defined in claim 5 in which the cooperating limiting means carried by the outer container is an inwardly-extending flange at the open end of the side walls thereof.

9. A self-heating container as defined in claim 5 in which the cooperating limiting means carried by the outer container is an inwardly-extending projection adjacent and inwardly from the open end of the side walls thereof.

10. A self-heating container as defined in claim 5 in which means are provided at the open end of the outer container for making a hermetic seal with the side walls of the food container.

11. A self-heating container as defined in claim 1 in which material of good heat-conductive properties extends into the body of the exothermic material and is in good heat-exchange relationship with the adjacent end of the food container.

12. A self-heating container comprising an outer container, a food container of heat-conductive material within the outer container and telescopically movable therein, a plurality of telescopic receptacles of good heat-conductive material between adjacent ends of the food container and the outer container, said receptacles making a good heat-conductive contact with the adjacent end of the food container, an exothermic material which on reaction with water liberates heat and expands within said receptacles, whereby when the exothermic material within the receptacles is activated, the receptacles will conduct heat from said material to the adjacent end of the food receptacle.

13. A self-heating container as defined in claim 12 which includes means for limiting telescopic movement of the food container within the outer container when the food container is subjected to the force of the expanding exothermic material.

14. A self-heating container as defined in claim 13 in which the receptacles generally are sector shaped.

15. A self-heating container as defined in claim 13 which has heat-insulating means between the outer edges of the receptacles and the outer container.

16. A self-heating container as defined in claim 13 which has heat-insulating material between said receptacles and the adjacent end of the outer container.

17. A self-heating container as defined in claim 13 in which a layer of the exothermic material is between said receptacles and the adjacent end of the outer container to heat insulate the receptacles from the outer container.

18. A self-heating container as defined in claim 13 in which the walls of the receptacles nearest the adjacent end of the outer container have openings therein for the passage of water to the exothermic material.

19. A self-heating container as defined in claim 13 in which the walls of the receptacles nearest the adjacent end of the outer receptacle have openings therein for the passage of water to the exothermic material, and in which portions of said walls of the receptacles adjacent the openings are bent inwardly into the exothermic material.

20. A self-heating container as defined in claim 13 in which the walls of the receptacles in contact with the food receptacle are shaped to accurately conform to the contour of the portion of

14

the wall of the food container with which they are in contact.

21. A self-heating container as defined in claim 13 in which the overlapping sides of the telescoping receptacles make a good heat-conductive contact with one another.

22. A self-heating container as defined in claim 13 in which the overlapping side walls of the telescoping receptacles are of sufficient height to remain in heat-conductive contact with one another when the food container has telescopically moved the maximum amount permitted by said movement-limiting means.

23. A self-heating container as defined in claim 13 in which members of good heat-conductive material are embedded in the exothermic material and continuously maintain contact with the walls of the receptacles nearest the food container during expansion of the exothermic material and provide a good heat-conductive path from within the mass of the exothermic material to said walls of the receptacles.

24. A self-heating container as defined in claim 23 in which said members of good heat-conductive material are an expansible mass of flexible material.

25. A self-heating container as defined in claim 23 in which said members of good heat-conductive material are springs.

26. A self-heating container as defined in claim 23 in which said members of good heat-conductive material are spring members having a flat central portion in contact with the walls of the receptacles which contact the food container, and radial fingers extending from said flat central portion into the mass of exothermic material.

27. A self-heating container as defined in claim 1 in which flexible members of good heat-conductive material are attached to the wall of the food container adjacent the exothermic material and extend into the exothermic material.

28. A self-heating container as defined in claim 12 in which the end of the outer receptacle has means for retaining a body of water to activate the exothermic material.

29. A self-heating container as defined in claim 28 in which the water-retaining means comprises a gauge ring telescopically mounted on said end of the outer receptacle and means for limiting the outward movement of said gauge ring.

30. A self-heating container as defined in claim 28 in which the water-retaining means comprises an inwardly-concaved end wall at said end of the outer container.

31. A self-heating container as defined in claim 12 in which means are provided for hermetically sealing the outer container.

32. A self-heating container as defined in claim 12 in which the outer receptacle comprises a bottom and side walls and a cover that extends over the food container and has side walls overlapping and hermetically sealed to the side walls of the outer receptacle.

33. A self-heating container as defined in claim 12 in which the receptacles generally are sector shaped and have their radial side walls terminating short of one another at their inner ends to provide an opening into each receptacle at its apex, and a central space communicates with the respective openings at the apices of the receptacles.

34. A self-heating container as defined in claim 1 in which the end of the food container adjacent

the exothermic material has a concave portion extending well into said container to provide space for the exothermic material.

35. A self-heating container for frozen foods which comprises an outer container, a food container of heat-conductive material within the outer container and telescopically movable therein, an exothermic material which on reaction with water liberates heat and expands between one end of the food container and the corresponding end of the outer container, means for limiting telescopic movement of the food container within the outer container when the food container is subjected to the force of said expanding material, and similar exothermic material between the food container and the other end of the outer container.

36. A self-heating container as defined in claim 35 in which the exothermic material at said other end is in a receptacle of good heat-conductive material which has a good heat-conductive contact with said other end of the food container, in which the outer container is an open-ended one having a bottom and side walls, and in which a cover member extends over the food container and the receptacle for the exothermic material at said other end of the food container and has side walls overlapping the side walls of said open-ended outer container.
